Harry A. Douglas.
By G. A. Gragg Atty.

UNITED STATES PATENT OFFICE.

HARRY A. DOUGLAS, OF BRONSON, MICHIGAN, ASSIGNOR TO DOUGLAS & RUDD MFG. CO., OF BRONSON, MICHIGAN, A CORPORATION OF MICHIGAN.

CIRCUIT-CONNECTOR.

1,377,411.

Specification of Letters Patent. Patented May 10, 1921.

Application filed October 24, 1917. Serial No. 198,339.

To all whom it may concern:

Be it known that I, HARRY A. DOUGLAS, a citizen of the United States, residing at Bronson, in the county of Branch and State 5 of Michigan, have invented a certain new and useful Improvement in Circuit-Connectors, of which the following is a full, clear, concise, and exact description.

My invention relates to the formation of 10 tubular shells and also to the assembly of shells with contact carrying cores or other cores and arms or lugs.

The invention has for one of its objects 15 an improved formation of a shell from a sheet of metal or other suitable material wherein opposite edges of the metal sheet are caused to abut. In carrying out this object of the invention in the preferred way, I form in both of two parallel edge portions 20 of the metal sheet tenons having stems and heads and which are alternated with similarly shaped mortises. All of the mortises and tenons are preferably of equal dimensions and the tenons upon each of the said 25 two edge portions of the sheet are received in the mortises in the other of such edge portions of the shell when the sheet is properly curled to form a shell. The mortises and tenons are desirably of T-shape, the in- 30 terengaging inner edges of the tenons preventing the shell from being expanded and the outer edges of the tenons, by engaging the base edges of the mortises, preventing the shell from being contracted.

35 In accordance with another object of my invention a shell, whether it is constructed as above set forth or otherwise, has an outer bulging portion along and within which an arm extends. This bulging portion of the 40 shell permits a contact carrying core that conforms in cross section to the bore of the shell to be placed within the shell in the same zone with the arm that is received in the bulging portion of the shell, while allowing such arm to be confined between the 45 contact carrying core and the metal of the shell. The shell also desirably carries a lug spaced apart from the aforesaid bulging portion of the shell and which co-operates 50 with the bulging portion of the shell, and preferably also the contact carrying core, to hold the arm and shell in assembly without the aid of a fastening screw. This arm has a continuation that extends to the exterior of the shell through an opening pro-

vided through a side of the shell. This continuation desirably forms, with said arm, an angular lug whereby the shell may be mounted, such continuation itself constituting an arm of such lug. 60

I will explain my invention more fully by reference to the accompanying drawing in which Figure 1 illustrates a sheet of metal stamped into a shape that will permit it to be formed into the shell of my invention; and Fig. 2 is a longitudinal sectional view of a shell formed from the sheet shown in Fig. 1. 65

Like parts are indicated by similar characters of reference throughout the different 70 figures.

The shell 1 is made from a sheet of metal 2 shown in Fig. 1. The shell has bayonet slots 3, 4 which are stamped in the sheet, each of the bayonet slots 4 being partially 75 formed in two opposite parallel edge portions of the sheet as indicated at 4¹, the portions 4¹ matching, when the sheet is curled, to form the bayonet slots 4. In these same opposite edges of the sheet 2 mortises 5 are 80 formed, the mortises at one of these edge portions of the sheet being in different zones from the mortises in the other edge portion of the sheet. These mortises are so shaped as to leave tenons alternating therewith, 85 each tenon having an outer head 6 and a stem 7 joining the head with the body of the sheet or shell, the narrow portion of each mortise being outermost to receive a tenon stem while the larger portion of each 90 mortise is innermost to receive a tenon head. The tenons at one edge of the sheet are in different zones from the tenons at the other edge of the sheet. Each tenon is desirably in the shape of a T but I do not wish to be 95 limited to the projection of the head of each tenon upon both sides of its stem. All of the mortises and tenons are of equal dimensions and the tenons upon each of the said two edge portions of the sheet are received 100 in the mortises in the other of such edge portions of the sheet when the sheet is properly curled to form the shell. The interengaging inner edges 6¹ of the tenons prevent the shell from expanding and the outer edges 6² of the tenons, by engaging the base edges 5¹ of the mortises, prevent the shell 105 from contracting. The edges 6¹, the outer edges of the T-heads, and the inner edges of the mortises extend longitudinally of the 110

shell and are desirably substantially parallel with its axis. A curled shell having joints thus made possesses advantages over one having dovetailed joints employing no well defined stems and heads and which have sides that slope with respect to the axis of the shell, the new construction preventing the shell from contracting and expanding.

The shell herein shown is of particular service in the structure forming the subject matter of the division of this application Serial No. 236,083, filed May 23, 1918 and, when thus employed, includes the formations 10, 14 and 15 which form no particular part of the invention in the present case.

The claims relating to the improved assembly of the shell and core are contained in my Patent 1,308,172, dated July 1, 1919.

While I have herein shown and particularly described the preferred embodiment of my invention I do not wish to be limited the precise details of construction shown as changes may readily be made without departing from the spirit of the appended claims, but having thus described my invention I claim as new and desire to secure by Letters Patent the following:

1. A shell formed of a curled sheet having each of two opposite edge portions formed with alternated similarly shaped equally dimensioned T-shaped mortises and tenons, the mortises in each edge portion receiving the tenons upon the other edge portion, the longitudinal edges of the heads of the tenons and mortises being substantially parallel with the axis of the shell.

2. A shell formed of a curled sheet having each of two opposite edge portions formed with alternated similarly shaped equally dimensioned mortises and tenons, the mortises in each edge portion receiving the tenons upon the other edge portion, said tenons having heads and stems connecting the heads with the balance of the shell, while the mortises have narrower portions outermost that receive the stems of the tenons and larger portions innermost that receive the heads of the tenons, the longitudinal edges of the heads of the tenons and the mortises being substantially parallel with the axis of the shell.

3. A shell formed of a curled sheet having each of two opposite edge portions formed with alternated similarly shaped

equally dimensioned T-shaped mortises and tenons, the mortises in each edge portion receiving the tenons upon the other edge portion.

4. A shell formed of a curled sheet having each of two opposite edge portions formed with alternated T-shaped mortises and tenons, the mortises in each edge portion receiving the tenons upon the other edge portion, the longitudinal edges of the heads of the tenons and mortises being substantially parallel with the axis of the shell, the inner longitudinal edges of the heads of the tenons upon each of said edge portions being in engagement with the inner longitudinal edges of the heads of the tenons upon the other of said edge portions to prevent the shell from expanding.

5. A shell formed of a curled sheet having each of two opposite edge portions formed with alternated mortises and tenons, the mortises in each edge portion receiving the tenons upon the other edge portion, said tenons having heads and stems connecting the heads with the balance of the shell, while the mortises have narrower portions outermost that receive the stems of the tenons and larger portions innermost that receive the heads of the tenons, the longitudinal edges of the heads of the tenons and the mortises being substantially parallel with the axis of the shell, the inner longitudinal edges of the heads of the tenons upon each of said edge portions being in engagement with the inner longitudinal edges of the heads of the tenons upon the other of said edge portions to prevent the shell from expanding.

6. A shell formed of a curled sheet having each of two opposite edge portions formed with alternated T-shaped mortises and tenons, the mortises in each edge portion receiving the tenons upon the other edge portion, the inner longitudinal edges of the heads of the tenons upon each of said edge portions being in engagement with the inner longitudinal edges of the heads of the tenons upon the other of said edge portions to prevent the shell from expanding.

In witness whereof I hereunto subscribe my name this 25th day of September, A. D. 1917.

HARRY A. DOUGLAS.
